P. HAAS

INLET VALVE MECHANISM FOR FLUSH TANKS

Filed June 9, 1925

Patented Mar. 16, 1926.

1,576,600

UNITED STATES PATENT OFFICE.

PHILIP HAAS, OF DAYTON, OHIO.

INLET-VALVE MECHANISM FOR FLUSH TANKS.

Application filed June 9, 1925. Serial No. 35,872.

To all whom it may concern:

Be it known that I, PHILIP HAAS, a citizen of the United States, residing at Dayton, in the county of Montgomery and State of Ohio, have invented certain new and useful Improvements in Inlet-Valve Mechanism for Flush Tanks; and I do hereby declare the following to be a full, clear, and exact description of the invention, such as will enable others skilled in the art to which it appertains to make and use the same.

My invention consists in the novel features hereinafter described, reference being had to the accompanying drawing which illustrates one form in which I have contemplated embodying the invention and which has been selected by me for purposes of illustration, and the said invention is fully disclosed in the following description and claims.

The object of my invention is to provide an inlet valve for flushing tanks of extremely simple character, which can be cheaply constructed and will be certain in operation, the parts of the valve mechanism being readily accessible and the separate parts thereof readily replaceable in case of wear. My invention also contemplates the operation of the valve by means of a float lever which is demountable with respect to the valve mechanism proper, so that it may be instantly removed and replaced by hand when desired.

Referring to the accompanying drawing, Fig. 1 represents a flush tank provided with a flushing valve embodying my invention, a portion of the tank being broken away to show the location of the valve and its pipe connections.

Fig. 2 is an enlarged sectional view of the valve mechanism and the adjacent portion of the valve operating float lever.

Fig. 3 is a vertical section on the line 3—3 of Fig. 2.

Fig. 4 is an enlarged detailed view, partly in section, showing a removable plug forming part of the valve mechanism and carrying the removable inlet valve seat.

Fig. 5 is an enlarged detailed view partly in section, of the inlet valve.

Fig. 6 is a detailed view also enlarged, of a portion of the valve actuating float lever adjacent to the valve.

In the said drawings, 1 represents a flush tank provided with a removable cover, 2, and having an outlet for the flushing pipe,

3, provided with any usual or preferred form of flushing valve mechanism, which is not shown herein as the same forms no part of my present invention. 4 represents the water inlet pipe connected with the tank by a fitting indicated at 5, in any usual or well known manner, to which a vertical pipe, 6, is connected and extends to a point near the top of the tank where the inlet valve is located, the entire inlet valve or at least the upper portion of the same being preferably above the water level so that access may be had to it for the purpose of removing and replacing parts without wetting the fingers. 7 represents a downwardly extending discharge pipe from the valve casing, terminating a short distance above the bottom of the tank, which is preferably employed for delivering the water from the valve casing to the tank without undue noise. The normal water level in the tank is indicated in Fig. 1 by a dotted line. 8 represents the valve casing which is divided by an angular partition, 9, into an inlet chamber, 10, and an outlet or discharge chamber, 11, connected by an aperture, 12, in a horizontal portion of the said partition. The upper part of the valve body is provided with a threaded aperture, 13, co-axial with the aperture, 12, to receive the threaded portion of a removable plug indicated at 14, and shown in detail in Fig. 4. This plug is provided at its upper end with a polygonal portion, 15, and a shoulder, 16, extending beyond the threaded portion and provided with a washer, 17, to engage the upper face of the valve casing and make a tight joint therewith. The plug is also provided with a central bore, 18, the lower portion of which is threaded to receive a removable collar, 19, the lower end of which is preferably rounded to form the valve seat, 20, for the inlet valve.

The collar, 19, is also provided with a polygonal shoulder portion, indicated at 21, between which and the lower face of the plug, a washer, 22, is provided, and held in position with respect to the plug. The removable collar, 19, is preferably made of a material which will not be affected injuriously by the water passing through the inlet valve mechanism at the particular point of installation. The character of water varies greatly and the metal which is not affected by the water in one installation, may be utterly useless in another. It is for this reason that I prefer to make the collar, 19, as a

separate part and attach it to the plug in the manner shown, so that these collars may be made up in different metals, as brass, Monel metal, nickel-silver, or any other suitable material, and a collar of the proper and most desirable material to withstand the particular water with which it is to be used can thus be supplied with any of my inlet valve mechanisms. The plug, 14, is also provided with an annular groove indicated at 23, the inner wall of which is pierced with a plurality of apertures indicated at 24, communicating with the interior of the bore, 18. The plug, 14, is screwed into the threaded aperture, 13, at the top of the valve casing, and screwed down so as to bring the washer, 22, in engagement with a seat indicated at 25, on the upper face of the horizontal portion of the partition, 9, surrounding the aperture, 12, forming a tight joint at both points so that the inlet chamber, 10, will then communicate with the discharge chamber, 11, through the groove, 23, apertures, 24, and a central opening in the collar, 19, under the control of the inlet valve.

The bottom of the valve casing is provided with a bearing aperture, 26, in axial alignment with the aperture, 12, to receive the inlet valve illustrated in detail in Fig. 5, which comprises a metallic cylindrical valve body or plunger, 27, having an axially aligned recess in its upper end, in which is located the valve proper, 28, formed of rubber, fibre, or other suitable material, of a diameter suitable to engage the valve seat, 20, and close the aperture through the collar, 19, and the valve body is preferably provided with a conical lower end indicated 29. The valve body is also provided with a pair of depending lugs indicated at 30—30, carrying a pivot pin, 31, which is adapted to be detachably engaged in a recess, 32, in a flattened end portion, 33, of a float actuated lever, 34, the outer end of which is provided with a float indicated by dotted lines in Fig. 1, at 35, and which is preferably of the kind described in my former application for Letters Patent of the United States, filed March 24, 1925, and given Serial No. 17,856, although any other form of float mechanism may be employed in connection with this inlet valve mechanism. When the recess, 32, of the float lever, is in operative engagement with the pivot pin, 31, the lever will be in position to operate the inlet valve and when the float is in raised position as shown by dotted lines in Fig. 1, the lever will engage the conical end, 29, of the valve body, 27, and force it upwardly so that the valve proper, 28, will engage the valve seat, 20, and shut off the flow of water against the pressure thereof. It will be noted that the point of engagement of the conical end of the valve body, 27, is closely adjacent to the pivot pin, 31, thus giving a sufficient lever-

age to the float lever to insure the closing of the valve against any water pressure that would be used in connection with a float tank of this character.

The valve body, 27, is preferably made of 70 Tobin bronze or nickel silver, so that it will not corrode and thus become stuck in the bearing aperture, 26, of the valve casing, and the pin, 31, will preferably be made of 75 Monel metal so that it will not be affected by the water. The correct operation of the inlet valve mechanism of a flush tank is of great importance to the successful operation 80 of the flushing system in which it is used. In the ordinary inlet valve as heretofore constructed, the valve seat frequently becomes corroded or eaten away by some material in the water, so that the valve does not correctly seat and leakage produces waste of water and frequently unnecessary 85 flushing action, with the accompanying noise and useless waste of water, which on metered service or in congested residence districts is extremely objectionable and expensive. Another difficulty in the ordinary use of inlet 90 valves is the wearing of the seat engaging valve proper, which usually requires the offices of a skilled plumber to correct. Another source of difficulty in the operation of 95 inlet valves is the sticking of a valve where a movable valve of the plunger type, such as is shown in the accompanying drawing, is employed. I obviate all of these difficulties by providing the removable collar, 19, which is especially designed to withstand the 100 particular water with which the device is to be used and therefore will operate for a very extended period without any breaking down of the valve seat, 20. Should this happen, it is only necessary to unscrew the plug, 105 14, which is readily accessible, and replace the collar, 19, with a new collar. The valve body, 27, is also made of a material which will withstand the action of the water with 110 which it is to be used, and in case it should become necessary to remove the valve body, 27, or the packing or valve proper, 28, this can be readily done by opening the flush valve and emptying the tank, permitting the lever, 34, to fall, and then detaching the 115 lever from the pin, 31, which will permit the valve body, 27, to drop out and a new one can be pushed up into its place, and the lever, 34, restored to its operative connection with the pin, 31. Additional collars, 19 and 120 valves, 27, (with the valve proper or packing, 28) will be furnished with my improved inlet valve mechanism for the purpose of renewing these parts should it become necessary, and this can be done at any time by 125 an ordinary householder without calling in skilled labor.

The valve body or plunger is also provided with a conical end portion, 29, as before described, and the upward pressure exerted by 130

the float lever, 34, will always be substantially axial with respect to the said valve body or plunger, so that there will be no tendency for it to bind in its vertical movements. If desired, the plunger valve can be removed by moving it upwardly through the aperture, 12, by removing the plug, 14, and reaching the valve by sticking a pin or sharp implement in the rubber packing, 28, or otherwise lifting it out of its guiding aperture.

What I claim and desire to secure by Letters Patent is:

1. Inlet valve mechanism for flush tanks, comprising a valve casing provided with an interior partition having an aperture therein, said casing having apertures in its upper and lower portions co-axial with said partition aperture, a plug fitting in the upper aperture in the casing and closing the same and having a sealing engagement with said partition, said plug having an interior bore and lateral openings communicating with the bore and with the interior of the valve casing, a collar detachably secured to said plug extending through the aperture in said partition, and provided at its lower end with a valve seat, a plunger valve engaging in the bottom aperture of the casing, having a recess at its upper end co-axial with the valve seat and a removable valve proper seated in the said recess for engaging said valve seat and movable float actuated means having portions operatively engaging said plunger valve.

2. Inlet valve mechanism for flush tanks comprising a valve casing provided with an interior partition having an aperture therein, said casing having apertures in its upper and lower portions co-axial with said partition aperture, a plug fitting in the upper aperture in the casing and having a portion closing the partition aperture, said plug having an interior bore provided with threaded portions at its lower end and lateral openings communicating with said bore and with the interior of the valve casing, a collar

having threaded portions detachably engaging the threaded portions in the bore of said plug, and having a valve seat at its lower end, said collar extending through said partition aperture, a plunger valve engaging in the bottom aperture of said casing, having an axial recess at its upper end and a valve proper fitted in said recess for engaging said valve seat, said plunger valve having a conical portion extending below the valve casing, said valve casing being provided with a pair of lugs below the same on opposite sides of said plunger valve, a horizontal pivot pin engaging said lugs and a float lever for engaging said valve and having a recess for detachably engaging said pivot pin.

3. Inlet valve mechanism for flush tanks comprising a valve casing provided with an internal partition, having an aperture therein, said valve casing having co-axial apertures in its upper and lower portions, a removable plug for engaging in said upper aperture of the valve casing, having a central bore, and lateral apertures communicating therewith and with the interior of the valve casing, a detachable collar having a threaded portion for engaging said plug, communicating with said central bore thereof, and provided with a lateral, polygonal shoulder, a washer engaging the lower end of said plug and held in position with respect thereto by said shoulder of the collar, said washer seating on the portion of the partition surrounding said aperture therein, the lower end of said collar forming a valve seat and extending below the partition aperture, a plunger valve mounted in the bottom aperture of the valve casing and carrying at its upper end packing material forming the valve proper, to engage said seat, and a float lever having a pivotal engagement with the valve casing and engaging the lower end of said plunger valve.

In testimony whereof I affix my signature.

PHILIP HAAS.
